(57) **CLAIM**

The ornamental design for a tweezer holder, as shown and described.

DESCRIPTION

FIG. 1 is a perspective view of a tweezer holder showing my new design;

FIG. 2 is a perspective view of the tweezer holder in an open position housing a tweezer;

FIG. 3 is a front elevational view of the tweezer holder thereof;

FIG. 4 is a rear elevational view of the tweezer holder thereof;

FIG. 5 is a left side elevational view thereof;

FIG. 6 is a right side elevational view thereof;

FIG. 7 is a top plan view thereof; and,

FIG. 8 is a bottom plan view thereof.

The tweezer shown in broken lines is for illustrative purposes only and forms no part of the claimed design.
